UNITED STATES PATENT OFFICE

2,117,450

BONDING RAIL JOINT TIE

Dean Royden Richardson, New Kensington, Pa.

Application January 29, 1938, Serial No. 187,746

1 Claim. (Cl. 238—59)

This invention appertains to new and useful improvements in ties and more particularly to a tie for bonding track joints.

The principal object of the present invention is to provide a tie which can be quickly disposed in place and which incidental to its placement will serve to bond one of the joints.

Another important object of the invention is to provide a tie of this construction which will be a simple construction and not susceptible to the ready development of defects.

These and various other important objects and advantages of the invention will become apparent to the reader of the following specification.

In the drawings:—

Figure 1 represents a fragmentary top plan view showing rails laid across the improved tie.

Figure 2 is a sectional view taken substantially on the line 2—2 of Figure 1.

Figure 3 is a bottom plan view of one of the cleats.

Figure 4 is a sectional view taken substantially on the line 4—4 of Figure 1.

Figure 5 is a fragmentary bottom plan view of the structure shown in Figure 4.

Figure 6 is a sectional view taken substantially on the line 6—6 of Figure 1.

Figure 7 is a fragmentary end elevational view showing the tie.

Figure 8 is a plan view of the bonding plate.

Referring to the drawings wherein like numerals designate like parts, it can be seen that numeral 5 represents the rail of one track while numerals 6—6 represent the adjoining rail sections of the complementary rail line.

The tie 7 is of channeled construction, the same in one end being provided with a cleat plate 8 riveted as at 9 to the tie 7 for engaging the base 40 of the rail section 5 at one side while the opposite side of this rail 5 is engaged by the cleats 10—10 each of which is provided with a boss 11 for engagement into a recess 12 in the top of the rail 7. Each of these cleats 10 is provided with an upwardly curved outer end portion 13 and is riveted in place as at 14.

The bonding end of the tie consists of the elongated clamp plate 15 riveted in place as at 16 for engaging the outer side of the rails 6—6 at the joint 17.

The top of the tie 7 at the opposite side of

the rail joint 17 has a rectangular-shaped opening 18 therein in which the depending portion 19 of the laterally curved clamp plate 20 is operative.

A plate 21 welded or otherwise secured to the bottom side of the tie 7 at a point underlying the rail joint 17 has the threaded shank extension 22, this extension being reduced with respect to the portion 23 to define the shoulder 24 against which the bonding plate 25 can bear.

The bonding plate 25 has its upper end portion cut downwardly as at 26 toward its intermediate portion to define the upwardly disposed upper corner portions 27 which are bent over and against the face portions of the rail sections 6—6 when the clamp plate 20 rides onto the base of the rail sections 6—6 under the feeding action of the nut 28 on the threaded shank 22. A cross pin or cotter pin 29 through the shank 22 prevents displacement of the nut 28 from the shank.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:—

A rail bonding tie comprising a tie having a top surface and having a rail attaching structure at one end and a rail attaching and bonding structure at its opposite end, the latter structure consisting of a rail engaging cleat fastened to the tie at the outer side of the rail bases for bridging a pair of rail ends, a threaded shank extending inwardly from the bottom of said surface of the tie from a point under the rails and having a shoulder thereon formed adjacent the inner edge of the rail bases, a bonding plate for abutting said shoulder bridging the abutting ends of the rails 40 at the bases thereof, said top surface having an opening extending inwardly from a point adjacent said inner rail base edges and a clamp plate 45 slidable on the shank and against the rail bases for forcing the bonding plate into snug bridging engagement with the abutting ends of the rails and into engagement with said shoulder and means on the shank for feeding the clamping plate into bonding position said bonding plate and clamp plate being received in said opening.

DEAN ROYDEN RICHARDSON.
